VENETIAN BLIND MECHANISM

Rudolph Cusumano, San Gabriel, Calif., assignor
to Lorentzen Hardware Mfg. Corp., New York,
N. Y., a corporation of New York

Application April 22, 1949, Serial No. 89,024

8 Claims. (Cl. 160—167)

1

This invention relates to Venetian blinds; and it embraces a method of, and apparatus for, displacing the plane of the blind generally parallel to itself.

In providing a window with a Venetian blind, the blind is either mounted to hang nested within the frame of the window or mounted to hang on the room side of the window jambs. The first type of mounting is referred to in the trade as an "inside" mounting, the second as an "outside" mounting. In an inside mounting, the blind is so positioned that the slats, when in horizontal position, will clear the window sash by a small amount. In an outside mounting, the slats are long enough to overlap a portion of the front faces of the jambs; and the blind is so positioned that the slats, when in horizontal position, will clear the front faces of the jambs by a small amount.

When the blind is tilted, the overall horizontal thickness of the array of slats is reduced. This results in a vertical so-called light line between each end of the blind and the sash in the case of an inside mounting, and between each end of the blind and the front of the jambs in the case of an outside mounting. These light lines are objectionable in that they admit light and, in some cases, provide a zone through which a person outside can peer into the room. Considerable effort and expense has been directed toward the elimination of these vertical light lines; see, for example, patent to J. W. Dunn 2,413,754 issued January 7, 1947.

An object of the present invention is to provide a simple, effective and inexpensive method of eliminating the vertical light lines which occur at the ends of a Venetian blind when the same is tilted.

Another object of the invention is to provide, in connection with a Venetian blind, simple, inexpensive and effective means for eliminating vertical light lines at the ends of the blind.

Another object is to provide an inexpensive Venetian blind in which the plane of the blind is automatically displaced, as towards the window, when the blind is tilted.

A further object is to provide simple, reliable and inexpensive equipment or fittings which can be applied to a Venetian blind to displace the plane thereof.

Still further objects are to provide a generally improved method of displacing the plane of a Venetian blind, and to provide generally improved means for accomplishing that result.

Further objects, and objects relating to details

2

and economies of construction, manufacture and use, will more definitely appear from the detailed description to follow.

My invention is clearly defined in the appended claims. In the claims, as well as in the description, parts may at times be identified by specific names for clarity and convenience; but such nomenclature is to be understood as having the broadest meaning consistent with the context and with the concept of my invention as distinguished from the pertinent prior art. The best forms in which I have contemplated applying my invention are illustrated in the accompanying drawings forming part of this specification, in which:

15 Fig. 1 is a perspective view showing a Venetian blind mounted inside a window frame.

Fig. 2 is a fragmentary cross section, on an enlarged scale, taken generally on the line 2—2 of Fig. 1 and the slats of the blind being shown in horizontal position.

20 Fig. 3 is a view similar to Fig. 2 but with the slats in tilted position.

Fig. 4 is a somewhat diagrammatic perspective view showing one element of my fitting in conjunction with a fragment of the tilt bar.

25 Fig. 5 is a perspective view showing another element of my fitting.

Fig. 6 is a perspective view showing a second form of fitting embodying the present invention.

30 Fig. 7 is a partly diagrammatic cross-sectional view showing how the invention may be applied to a blind of the enclosed metal head type.

Fig. 8 is a perspective view showing the blind-displacing rocker of Fig. 7.

35 Fig. 9 is a perspective view showing the cam fitting of Fig. 7 that actuates the blind-displacing rocker.

Fig. 1 shows a window frame designated as a whole by 10 having a Venetian blind mounted inside thereof. The blind (see also Figs. 2 and 3)

40 consists essentially of an array of slats 11 supported in conventional manner by a pair of ladder tapes 12, 12 which are attached to and depend from a tilt bar 14. The tilt bar is mounted for oscillation on a horizontal axis at 15, which may be established by suitable pivotal connection at the ends of the tilt bar to supporting brackets which are attached to and depend from a head bar 16. One such tilt bar bracket is shown at 17

45 in Figs. 2 and 3 and, as is well understood in the art, one of these supporting brackets may be equipped with means (not shown) for tilting the tilt bar. To obscure the tilt bar and operating mechanism, a fascia board or the like 18 may be attached to the head bar 16. The blind is adapted

to be raised and lowered in conventional manner by lift cords 19 and is adapted to be tilted by tilt cords 20 which actuate the tilting mechanism of the blind.

The Venetian blind construction just described is conventional in the art, and other suitable Venetian blind arrangements which are known to the art may be substituted therefor.

With the inside mounting shown in the drawings, the slats of the blind, when in horizontal position, clear the window sash 21 by a slight amount as shown in Fig. 2. When the blind is tilted in either direction, the sash-adjacent edges of the slat are moved away from the plane of the window, thereby producing a light line between the ends of the blind and the sash unless some steps are taken to prevent the formation of such a light line. In the case of an outside mounting, both the head bar and the slats are somewhat longer. The head bar is usually supported by suitable brackets attached to the front faces 22, 22 of the window jambs, the slats of the blind being long enough to overlap the front faces of the jambs for an appreciable distance, as by extending from A to A in Fig. 1. With such an outside mounting, the slats of the blind, when in horizontal position, clear the front faces of the jamb by a small amount; and when the slats are tilted, vertical light lines are formed between the ends of the blind and the front faces of the jambs 22, 22 unless steps are taken to prevent the formation of such light lines.

In accordance with my invention, the vertical plane of the blind is displaced towards the window as the blind is tilted in either direction. This displacement prevents the formation of the vertical light lines between the blind and the window sash in the case of an inside mounting, and between the blind and the front faces of the jambs in the case of an outside mounting. This displacement is preferably effected automatically by means associated with each ladder tape of the pair of ladder tapes shown in Fig. 1. In the event of the blind having more than two ladder tapes, it is usually sufficient to associate such blind-displacing means with the pair of ladder tapes that constitute the end ladder tapes of the blind.

The blind-displacing means associated with one of the ladder tapes is shown in Figs. 2, 3 and 4. A one-piece sheet metal bracket 25 is secured to the head bar 16 and pivotally supports a rocker 26. As shown in Fig. 5, the bracket 25 has a horizontal arm 27 provided with screw holes 28, 28 for attaching it to the head bar 16 as shown in Figs. 2 and 3. Depending from the horizontal arm 27 is a vertical arm 29 provided with a horizontal slot 30. The slot 30 is adapted to receive the rocker 26, which is perhaps best seen in Fig. 4. This rocker is a one-piece L-shaped sheet metal stamping having a relatively long depending arm 31 that is adapted to be inserted through the slot 30 until shoulders 32, 32 engage the depending arm 29. This leaves the rocker 26 free to swing pivotally with respect to bracket 25 by which it is supported. The rocker 26 also has a horizontal arm 34 which is adapted to overlie the tilt bar 14 and which may be bifurcated as shown so that the two branches of the arm 34 will lie on opposite sides of the slot 35 through which lift cord 19 passes.

The supporting bracket 25 and the rocker 26 constitute a blind-displacing means, and it will be understood that one such blind-displacing means is associated with each of the ladder tapes shown in Fig. 1. If the blind have more than 75

two ladder tapes, one such blind-displacing means will be associated with at least the pair of ladder tapes which constitute the end ladder tapes of the blind.

As the tilt bar is tilted in either direction to tilt the slats of the blind, the rocker arm 34 is cammed upwardly by the tilt bar, thus imparting rocking movement to the rocker 26. In response to this rocking movement, the depending arm 31 of the rocker forces its associated ladder tape towards the window. Thus, the rockers, acting on the two ladder tapes of the blind, displace the plane of the blind towards the plane of the window as the blind is tilted in either direction. This displacement prevents the formation of light lines between the ends of the blind and the window sash in the case of an inside mounting, and between the ends of the blind and the front faces of the window jamb in the case of an outside mounting.

A modified form of blind-displacing means is shown in Fig. 6 in which a U-shaped supporting bracket 40 is provided with screw holes 41, 41 for attaching it to the head bar 16 similarly to the attachment of supporting bracket 25. Pivotally mounted in the lower ends of the legs of bracket 40 is an L-shaped rocker member formed of stiff wire. This rocker, which operates in the same manner as rocker 26, has horizontal portions 42, 42 which are adapted to overlie the head bar and receive rocking movement therefrom, and has a U-shaped depending portion 44 which is adapted to engage the vertical branch of the ladder tape and displace it towards the plane of the window as the blind is tilted.

While Figs. 1-6 disclose my invention as applied to a Venetian blind having a wooden head bar and a wooden tilt bar, it should be understood that the invention is also applicable to other types of blinds, such as, for example, blinds of the enclosed metal head type. In enclosed metal head blinds, the tilt bar is usually in the form of a rod or other shaft, and my blind-displacing rockers may be actuated therefrom in any suitable manner. In fact, it is not even necessary that the blind-displacing rockers be actuated from the tilt bar, but only that they be actuated in any suitable manner upon tilting of the blind, being preferably linked to an operating part of the blind to automatically receive locking movement thereof.

Figs. 7, 8 and 9 show one way in which the invention may be applied to a certain type of enclosed metal head blind. Mounted in a U-shaped metal channel 50 is a cradle 51 having two longitudinally-spaced vertical webs 53 (one shown). Journaled in the tops of the webs 53 is a tilt bar in the form of a metal rod 52 of D-shaped cross section. Attached to the rod 52 and located between the two longitudinally-spaced webs 53 of the cradle is a tape drum 54 to which are secured the upper ends of the vertical branches 55, 55 of the usual ladder tape, these branches passing through slots at 56, 56 in the bottom of the channel 50. Upon rotation of the rod 52 in either direction, one of the vertical branches 55 of the ladder tape is raised while the other is lowered, thereby tilting the slats of the blind as is well understood. Also carried by the tilt bar 52 is a cam fitting 57 (see Fig. 9) which actuates a rocker 58 (see Fig. 8). Except for the addition of the cam fitting 57 and the rocker 58, the construction shown in Fig. 7 is more fully disclosed in the application of

Harry Nelson, Serial No. 778,002, filed October 4, 1947.

Referring to Fig. 8, the rocker 58 is a generally U-shaped member formed of stiff wire and having a relatively long depending arm 59 threaded through one of the slots at 56 in the channel 59, the particular slot being made wide enough to receive both the rocker and the vertical branch of the ladder tape. The length of this slot at 56 is only slightly greater than the width of the arm 59 so that shoulders 60, 60 rest on the bottom of the channel 50 and prevent the rocker 58 from descending to a position lower than that shown in Fig. 7. It will be seen that by this arrangement the rocker 58 is pivotally supported on an axis which is substantially in alignment with the shoulders 60, 60. Extending upwardly from the shoulders 60, 60 are motion-receiving portions 61, 61 which preferably are positioned adjacent to the confronting faces of the two vertical webs 53 of the cradle 51. These portions 61, 61 bear against cam elements 64, 64 of the cam fitting 57 which is mounted on the rod 52 between the two vertical webs 53 of the cradle. The connecting bar 65 of the cam fitting 57 lies in a longitudinal slot or opening in the top of drum 54. The cam elements 64, 64 are provided with slots 66, 66 so that these cam members may be forced onto the tilt bar 52 and be carried thereby, being laterally flexed in the process if necessary; or, if desired, the tilt bar 52 may be telescoped into the bar-receiving enlargements at the inner ends of slots 66, 66.

Upon rotation of the tilt bar 52 in either direction, the rocker 58 is swung counterclockwise as viewed in Fig. 7, thereby displacing the ladder tape and the plane of the blind, as previously described in connection with Figs. 1-5. If desired, the cam elements 64, 64 may be given different shapes in the upper and lower active quadrants shown in Fig. 7, so that the amount of displacement and rate of displacement of the blind will be different when the blind is tilted in the two directions. In fact, the cam elements may obviously be so shaped that the blind is displaced when it is tilted in one direction and not displaced at all when it is tilted in the opposite direction.

I claim:

1. In a Venetian blind for a window, the blind having a head bar, a tilt bar pivotally mounted beneath the head bar, a pair of ladder tapes spaced along the tilt bar and depending therefrom, and an array of slats supported by the ladder tapes; blind-displacing means operative to automatically displace the plane of the blind toward the plane of the window when the tilt bar is tilted to tilt the slats of the blind, said blind-displacing means comprising: supports attached to the head bar in association with the ladder tapes, and rockers pivoted to the supports on axes which are parallel to the axis of the tilt bar and which are positioned forwardly and upwardly of the axis of the tilt bar, each rocker having an arm extending over the tilt bar to receive rocking movement therefrom when the tilt bar is tilted and having a depending arm to engage the associated ladder tape and displace it toward the window in response to the rocking movement imparted to the rocker by the tilt bar.

2. In a Venetian blind, a head bar, a tilt bar pivotally mounted beneath the head bar, a pair of ladder tapes spaced along the tilt bar and

depending therefrom, and an array of slats supported by the ladder tapes; blind-displacing means operative to automatically displace the plane of the blind generally parallel to itself when the tilt bar is tilted to tilt the slats of the blind, said blind-displacing means comprising: supports attached to the head bar in association with the ladder tapes, and rockers pivoted to the supports on axes which are parallel to the axis of the tilt bar and spaced therefrom, each rocker having a portion extending adjacent to the tilt bar to receive rocking movement therefrom when the tilt bar is tilted and having a portion extending adjacent to the associated ladder tape to engage the same and displace it generally parallel to itself in response to the rocking movement imparted to the rocker by the tilt bar.

3. In a Venetian blind for a window, the blind having a tilt bar, a pair of ladder tapes spaced along the tilt bar and depending therefrom, and an array of slats supported by the ladder tapes; blind-displacing means operative to automatically displace the plane of the blind toward the plane of the window when the tilt bar is tilted to tilt the slats of the blind, said blind-displacing means comprising: supports mounted in association with the ladder tapes, and rockers pivoted to the supports on axes which are parallel to the axis of the tilt bar and spaced therefrom, each rocker having a portion operatively associated with the tilt bar to receive rocking movement therefrom when the tilt bar is tilted and having a portion extending adjacent to the associated ladder tape to engage the same and displace it toward the window in response to the rocking movement imparted to the rocker by the tilt bar.

4. For a Venetian blind having a tilt bar and a ladder tape depending therefrom; blind-displacing means comprising: a support having an attaching portion and a depending portion, and a rocker pivoted to the depending portion, the rocker having an arm to overlie the tilt bar and receive rocking movement therefrom and having a depending arm to engage and displace the ladder tape in response to the rocking movement received from the tilt bar.

5. For a Venetian blind having a tilt bar and a ladder tape depending therefrom; blind-displacing means comprising: a support for mounting in association with the upper portion of the ladder tape, and a rocker pivoted to the support, the rocker having a portion to receive movement from an operating part of the blind and having a portion to engage and displace a portion of the ladder tape which is a little below the upper end thereof.

6. For a Venetian blind having a tilt bar and a ladder tape depending therefrom; blind-displacing means comprising: a support for mounting in association with the upper portion of the ladder tape, and an L-shaped rocker pivoted to the support, one arm of the L-formation being adapted to overlie the tilt bar and receive rocking movement therefrom when the tilt bar is tilted, and the other arm of the L-formation being adapted to engage the ladder tape a little below the upper end thereof and displace it in response to the rocking movement received from the tilt bar.

7. In a Venetian blind having a tilt bar, a pair of ladder tapes supported along the tilt bar and depending therefrom, and an array of slats supported by the ladder tapes; blind-displacing

means operative to automatically displace the plane of the blind generally parallel to itself when the tilt bar is tilted, said blind-displacing means comprising: a pair of members having portions positioned adjacent to the upper portion of corresponding vertical branches of the ladder tapes and other portions in the path of rotation of the tilt bar, the tilting of the tilt bar serving to actuate said members and cause them to engage the ladder tapes and carrying them to a position in which the plane of the blind is displaced from its initial plane.

8. In a Venetian blind for a window, the blind having a tilt bar, a pair of ladder tapes spaced along the tilt bar and depending therefrom, and an array of slats supported by the ladder tapes; blind-displacing means operative to automatically displace the plane of the blind towards the plane of the window when the tilt bar is tilted

to tilt the slats of the blind, said blind-displacing means comprising: members having portions positioned immediately in front of the upper portion of corresponding vertical branches of the ladder tapes and other portions in the path of rotation of the tilt bar, the tilting of the tilt bar serving to actuate said members and cause them to engage the ladder tapes and carry them rearwardly to a position in which the plane of the blind is displaced towards the window.
